(57) **CLAIM**

We claim the ornamental design for a combination folding chair and toilet support for toddler, as shown and described.

DESCRIPTION

FIG. 1 is a perspective view of a combination folding chair and toilet support for toddler showing our new design; FIG. 2 is a front elevational view thereof; FIG. 3 is a top plan view thereof; FIG. 4 is a bottom plan view thereof; FIG. 5 is a right side elevation view thereof, the left side elevational view thereof being a mirror image thereof; FIG. 6 is a rear elevational view thereof; and, FIG. 7 is a left side elevational view showing hinged portions of the combination folding chair and toilet support for toddler in a use position, all other views showing the hinged portions angularly displaced from each other for clarity; the broken lines depict environmental structure for illustrative purposes only and form no part of the claimed design.
